DANIEL M. GRAY, EDWIN HAUB, AND JOHN J. WILLIAMS, OF WHEELING, WEST VIRGINIA, ASSIGNORS TO HAZEL-ATLAS GLASS COMPANY, OF WHEELING, WEST VIRGINIA, A CORPORATION OF WEST VIRGINIA.

CLOSURE FOR FOOD CONTAINERS.

Application filed June 18, 1925. Serial No. 37,914.

Fig. 1 is a partial section of a glass jar showing our improved closure or cap in position for application thereto; Figs. 2, 3 and 4 are similar sections showing the positions of the closure respectively just after the beginning of the sealing operation, in applied or sealed position, and the effect of internal pressure after application of the closure; Fig. 5 is a partial elevation of the jar shown in Figs. 1, 2, 3 and 4; Fig. 6 is a section of the closure shown in Figs. 1, 2, 3 and 4; and Fig. 7 is a section of a modified form of closure.

Our invention relates to caps or closures for food containers, such as glass receptacles, of the type which are made of metal which is soft and light enough to be torn readily with the fingers so as to permit easy removal. The objection to such closures is that they normally have not enough strength in the side walls or depending flanges to cause the rubber gaskets therein to seal the imperfections which are usually found in the glass of the containers as now made, for the reason that the flanges bulge and give way and thus fail to press the rubber gaskets tightly enough against the side walls of the glass to maintain a seal. In carrying out our invention and in eliminating these defects we reinforce the flange suitably, and such reinforcement, which may be in the form of a bead with an internal annular groove, provides room for a gasket, which as the closure is applied is forced outwardly into such groove, and thus permits the gasket to slide over the finish or lip of the glass and form a seal. Our invention also comprises various features which we shall hereinafter describe and claim.

Referring to the drawings, the closure or cap 2 is preferably made of very thin sheet metal such as aluminum, which may be easily torn with the fingers, and has a depending flange 3. In the flange 3 and at an appreciable space below its top edge is provided a bead 4, which on the inner face of the flange forms an annular groove 5, so positioned as to be opposite the lower portion of the gasket 6, which is preferably rectangular in cross-section, and seats against the inner face of the flange 3. Below the bead 4, the flange 3 has a constricted

portion 7, so as to support the gasket 6 in position ready for application to the jar 8. 55 The constricted portion 7 also acts as a reinforcement to the flange 3 and assists the bead 4 in stiffening the flange and in preventing it from bulging or deforming under pressure. 60

The jar or receptacle 8 preferably has the outer edge 9 of its lip bevelled, and below the bevelled edge or surface 9 are the vertical surfaces 10 and 11, and between them a depressed surface 12 and a second bevelled edge 13. Attached to the lower edge of the flange 3 are lugs or flaps 14, shown in Fig. 6, bent up on the outside of the flange, by which the flange may be torn out, thus breaking the seal and permitting the removal of 70 the closure.

The closure is applied to the glass receptacle as follows:

The closure is placed on top of the container in the position shown in Fig. 1, with the bottom edge of the gasket 6 resting on the bevelled surface 9 with the constricted portion 7 of the flange 3, which is of slightly larger diameter than the diameter of the surface 11, extending about that surface, 80 thereby serving to center the closure over the top of the container.

As the diameter of the gasket 6 is smaller than the diameter of the surface 10, considerable force is required to be applied to the top of the closure in order to force it down over the surface 10 of the container, and when this force is applied to the closure top the gasket 6 is compressed and its lower portion is forced outwardly into the groove 5, 90 as is shown in Fig. 3. The gasket 6 thus is permitted to slide down over the surfaces 9 and 10, and when its bottom portion passes below the surface 10 the compression of that portion is released and that portion of the 95 gasket expands into the depression 12, as is shown in Fig. 3, thus having a sealing engagement with the surfaces 9 and 10 and an interlock with the depression 12.

The interlock of the gasket in the depression 12 is of importance, since in sterilizing many food products the sealed packages are heated to a temperature which in some cases reaches 200° F. This heating creates an internal pressure which has a tendency to 105 force the cover off such packages, and there-

by spoil the contents. Hence, the desirability of having some means for retaining the closures on the container under such condition is manifest. This internal pressure condition is illustrated in Fig. 4.

In Fig. 7 we have shown a modified form of closure in which the constricted portion 7' of the flange 3' has an additional reinforcing bead 15.

The terms and expressions which we have employed are used as terms of description and not of limitation, and we have no intention, in the use of such terms and expressions, of excluding any equivalents of the features shown and described, or portions thereof, but recognize that various modifications are possible within the scope of the invention claimed.

What we claim is:

1. A closure for a food container composed of a relatively soft light metal having an imperforate top and a depending flange with a constricted lower portion; an annular reinforcing bead in said flange forming an internal annular groove; a plastic gasket engaging the constricted portion of the flange and the inner surface of the top and bearing against the inner surface of said flange, in combination with a container having an exterior annular projection immediately below the top edge thereof with a bevelled upper face; and a recessed portion below said projection; the lower portion of said gasket upon application of pressure to the top of the closure being arranged to be compressed into said groove upon being forced against said bevelled face and thereby to pass the said annular projection, and expand into said recessed portion below said projection; whereby the said gasket forms a seal against said projection and an interlock with the lower edge of such projection.

2. A closure for a food container composed of a relatively soft light metal comprising an imperforate top and a depending flange; a circumferential rib in said flange forming an internal groove; a plastic gasket seating upon the inner face of said flange and having a bearing upon the inner surface of the top; in combination with a container having annular faces of different diameters, one of which is greater than the internal diameter of said gasket; the said gasket prior to the application of pressure spanning but not entering the groove and upon the application of pressure to the top of said closure being arranged to be compressed into said groove and thereby to pass over the annular face of greater diameter, form a seal against said surface, and expand in the region of an annular face of a lesser diameter than the initial internal diameter of said gasket, and comprising a means for resisting internal pressures.

3. A closure for a food container composed of a relatively soft light metal having an imperforate top and a depending flange with a constricted lower portion, the constricted portion of said flange below said gasket being of appreciably less diameter than the interior diameter of any other part of the flange; an annular bead in said flange forming an internal annular groove; a plastic gasket engaging the constricted portion of the flange and the inner surface of the top and bearing against the inner surface of said flange; in combination with a container having an exterior annular projection immediately below the top edge thereof with a bevelled upper face; and a recessed portion below said projection; the lower portion of said gasket upon application of pressure to the top of the closure being arranged to be compressed into said groove upon being forced against said bevelled face and thereby to pass the said annular projection, and expand into said recessed portion below said projection; whereby the said gasket forms a seal against said projection and an interlock with the lower edge of such projection.

4. A closure for a food container composed of relatively light soft metal having an imperforate top and a depending flange with a substantially vertical inner face and with a constricted lower portion; an annular bead in said flange forming an internal annular groove; a plastic gasket seating against said vertical face and above said constricted portion; in combination with a container having an exterior annular projection with a circumferential bearing face; the said projection having a bevelled upper face extending to the top edge of the container at an angle to said projection, and a recessed portion below said projection; the lower portion of the gasket on the application of pressure to the top of the closure being arranged to be compressed into said groove upon being forced against said bevelled face, and thereby pass said projection and expand into said recessed portion below said projection, whereby the said gasket forms a seal against said projection and an interlock with the lower edge of such projection.

5. In closure means for glass containers, a cap member formed of sheet metal and having a relatively flat body portion provided at its edge with an annular flange member adapted to receive the mouth portion of the container, said annular flange member having a reduced diameter adjacent its free edge to provide an internal gasket-receiving seat between the reduced portion and the body portion of the cap member, and the gasket-receiving seat having a reinforcing bead formed therein.

6. In closure means for glass containers,

a cap member formed of sheet metal and having a relatively flat body portion provided around its edge with an annular flange member adapted to receive the mouth portion of the container, a substantial section of the flange member adjacent its free edge having a reduced diameter to provide an internal gasket-receiving seat between the reduced section and the body portion of the cap member, said gasket-receiving seat having a reinforcing circumferential bead formed therein, a gasket mounted in said seat, a lip member formed on the mouth portion of the container for engagement by said gasket, and a circumferential bead formed on the container in a spaced apart relation to the lip member, said gasket extending across the lip member into the recess between the lip and the bead, the reduced section of the cap flange member occupying an enclosing relation to the bead member. 15
